CLAIM

The ornamental design for a hand held voice actuated control apparatus, as shown and described.

DESCRIPTION

FIG. 1 is a perspective view of the hand held voice actuated control apparatus showing our new design;

FIG. 2 is a front elevational view;

FIG. 3 is a rear elevational view;

FIG. 4 is a side elevational view when viewed from the left side;

FIG. 5 is a side elevational view when viewed from the right side;

FIG. 6 is a top plan view; and,

FIG. 7 is a bottom plan view.
